UNITED STATES PATENT OFFICE.

HENRY H. HARRISON, OF NEW YORK, N. Y.

CIGARETTE-MAKER.

SPECIFICATION forming part of Letters Patent No. 681,053, dated August 20, 1901.

Application filed April 11, 1901. Serial No. 55,323. (No model.)

To all whom it may concern:

Be it known that I, HENRY H. HARRISON, a citizen of the United States, and a resident of the city of New York, borough of Manhattan, 5 in the county and State of New York, have invented a new and Improved Cigarette-Maker, of which the following is a full, clear, and exact description.

This invention relates to a cigarette-making device designed especially for use by persons in making cigarettes for their own consumption. The device may be made in the single form here illustrated or it may be made in any multiple. In the latter case a 10 framing or body portion will be provided to connect together the various parts, and this framing or body portion may be of any shape desired, either round, square, or in other forms, if preferred. Also the parts may be 15 constructed to make the cigarette round in cross-section or square, according to the desire of the user.

This specification is a specific description of one form of the invention, while the claim 20 is a definition of the actual scope thereof.

Reference is to be had to the accompanying drawings, forming a part of this specification, in which similar characters of reference indicate corresponding parts in all the views.

Figure 1 is a perspective view of the invention. Fig. 2 is a longitudinal section thereof. Fig. 3 is a cross-section of the charging-tube, and Fig. 4 is a cross-section of a slight modification thereof.

According to the construction here shown the body portion *a* is in the form of a cylindrical tube, preferably closed at its lower end by a cap *a'*. The upper end of this tube is open and has a lug *a''* thereon, such lug 30 carrying a closure-plate *b*, which is pivoted on the lug through the medium of a contracted neck *b'*. This closure-plate is capable of swinging to the open position (shown in Fig. 1) or to the closed position (shown in Fig. 2.)

Carried on the body-tube *a* is a box *c*, adapted to contain a suitable paste, this box being fitted with a sliding or otherwise-movable cover *c'*.

d indicates the charging-tube, which is arranged to fit snugly within the body-tube and which is formed with a longitudinal slot *d'*, extending throughout its length. The upper

end of the tube *d* has a flange *d''* formed thereon, which is adapted to overhang the upper end of the body-tube *a*.

In using the device the tube *d* is withdrawn from the body-tube and the cigarette-paper is rolled around this charging-tube, after which the edges of the paper are cemented together. The paper may be supplied with 55 cement or paste from the box *c*, or, if desired, the edges of the paper may be previously gummed, so that they need only be moistened when it is desired to secure the edges together.

The paper having been placed on the tube *d* 60 and fastened at its edges, the tube, with the paper, should be inserted into the body-tube. When the parts are thus adjusted, the charging-tube should be filled with tobacco, and when the proper amount has been inserted in 70

the tube the closure *b* should be thrown to the position shown in Fig. 2, in which the closure lies immediately over the closure *b*, with the neck *b'* opposite the slot *d'* in the charging-tube. By grasping the charging-tube at the 75

flange *d''* the tube may be drawn out of the body-tube, leaving the cigarette-paper within the body-tube and also leaving the tobacco in said tube, the charging-tube being moved from over the tobacco which was previously 80 pressed thereinto. In this operation the

closure-plate *b* acts to hold the tobacco in place, the charging-tube moving over the closure-plate and this plate therefore serving as an abutment to prevent the displacement 85 of the charge of tobacco. When the charging-tube has been withdrawn from the body-tube, the cigarette will be completed and it is only necessary to withdraw it from the body-tube. Now it is obvious that, as intimated above, the device may be constructed with any number of body and charging tubes 90

desired, and these tubes may be of any size or shape which the manufacturer may deem it advisable to give them.

In making cigarettes in which the tobacco is in long strips or strings, which is generally known as "long filler," the charging-tube may be constructed as shown in Fig. 4—that is to say, the tube *d* may have a part indicated at *d''*, 95 such part extending longitudinally throughout the length of the tube and being hingedly connected to the main portion of the tube by the hinge *d'*, the arrangement being such 100

that the swinging part d^3 cannot move inward beyond the position shown in Fig. 4, but the hinge d^4 allowing the part d^3 to swing downward to a sufficient extent to permit of conveniently directing the tobacco lengthwise, as shown in Fig. 2. With this form of the device the operation is the same as that previously described.

Various changes in the form, proportions, and minor details of my invention may be resorted to without departing from the spirit and scope of my invention. Hence I consider myself entitled to all such variations as may lie within the scope of my claim.

Having thus described my invention, I claim as new and desire to secure by Letters Patent—

A cigarette-maker, comprising a tubular

body portion, a charging-tube capable of slidably fitting within the body portion, the charging-tube having a longitudinally-extending slot therein, and a closure-plate having a contracted neck pivotally mounted on one end of the body portion, the closure-plate being capable of fitting within the charging-tube and the slot of said tube receiving the contracted neck of the closure-plate, for the purpose specified.

In testimony whereof I have signed my name to this specification in the presence of two subscribing witnesses.

HENRY H. HARRISON.
